US00D944390S

(12) **United States Design Patent** (10) **Patent No.:** **US D944,390 S**
(45) **Date of Patent:** **** Feb. 22, 2022**

(54) **VITAL INJECTOR**

(71) Applicant: **Xianlin He**, Zhanjiang (CN)

(72) Inventor: **Xianlin He**, Zhanjiang (CN)

(**) Term: **15 Years**

(21) Appl. No.: **29/778,572**

(22) Filed: **Apr. 14, 2021**

(30) **Foreign Application Priority Data**

Jan. 9, 2021 (CN) 202130013914.2

(51) **LOC (13) Cl.** **24-02**

(52) **U.S. Cl.**

USPC **D24/113**

(58) **Field of Classification Search**

USPC D24/112-114; 606/181, 185; 604/264,
604/272, 187, 181, 184, 227

CPC A61M 5/178; A61M 3/00; A61M 5/20

(57) **CLAIM**

The ornamental design for vital injector, as shown and described.

DESCRIPTION

FIG. 1 is a perspective view of a vital injector showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the vital injector and form no part of the claimed design.
